(57) **CLAIM**

The ornamental design for a keypad for control of lights and fans, as shown and described.

DESCRIPTION

FIG. 1 is a perspective view of a keypad for control of lights and fans according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a keypad for control of lights and fans according to a second embodiment of our new design.

FIG. 8 is a front view thereof, the left side, right side, top and bottom views of the second embodiment being identical to the left side, right side, top and bottom views of the first embodiment.

FIG. 9 is a perspective view of a keypad for control of lights and fans according to a third embodiment of our new design.

FIG. 10 is a front view thereof, the left side, right side, top and bottom views of the third embodiment being identical to the left side, right side, top and bottom views of the first embodiment.

FIG. 11 is a perspective view of a keypad for control of lights and fans according to a fourth embodiment of our new design; and,

FIG. 12 is a front view thereof, the left side, right side, top and bottom views of the fourth embodiment being identical to the left side, right side, top and bottom views of the first embodiment.
